ATTORNEY*

UNITED STATES PATENT OFFICE.

GEORGE A. CLUFF, OF CLIFTON, NEW JERSEY.

WARPING MACHINE.

Application filed June 25, 1923. Serial No. 647,466.

To all whom it may concern:

Be it known that I, GEORGE A. CLUFF, a citizen of the United States, residing at Clifton, in the county of Passaic and State 5 of New Jersey, have invented certain new and useful Improvements in Warping Machines, of which the following is a specification.

This invention relates to apparatus in 10 which a warp is wound on a beam or the like, as in a warping machine, and it has for one of its principal objects to provide improved means for stopping the rotation of the beam when a thread of the warp 15 breaks or becomes unduly slack; the mechanism as constructed for the accomplishing of this object includes a series of detectors or fallers respectively engaged with and controlled by the threads of the 20 warp, and a further object of the invention is to provide for the detectors being used to produce a "cross" in the warp, as in warping, i. e., an arrangement of the warp threads in which the alternates will be separated from the remainder.

In the drawings,

Fig. 1 is a side elevation of a warping apparatus embodying the invention;

Fig. 2 shows in front elevation the detectors and associated parts and the structure in which they are mounted; and

Fig. 3 is a horizontal section on line 3—3, Fig. 1.

A warping machine is shown of the type 35 illustrated in my Patent No. 1,377,751, but it will be understood that the invention may be applied to other warping machines or in fact to any machine in which a warp is wound on a beam or the like. The word 40 "beam" is herein used to define any rotary member on which a warp may be wound.

In the frame *a* is journaled a drive shaft *b* which may be suitably driven and on which is fixed a driving wheel *c*, this wheel being 45 peripherally grooved as in my said patent. A lever *d* is fulcrumed at *e* in the frame and in this lever is journaled one end of a shaft *f* on which is fixed a wheel *g* adapted to rest on the grooved periphery of and be 50 driven by the wheel *c*, the shaft having thereon a member *h* on which to wind the warp fixed in some way to rotate therewith. The beam is here taken as comprising the structure *f g h*.

On the frame may be journaled the drum 55 *a'* over which the warp extends, being held in peripheral contact therewith by the rollers *a²*; *a³* is the usual condensing reed.

Means is provided for stopping the rotation of the beam. In the present case there 60 is a support *i* which is here in the form of a lever. Another lever *j*, forming a cam device or chock, is fulcrumed on the shaft *f* and has one end adapted to bear against the support *i* and when the lever is turned 65 clockwise it elevates the beam out of contact with the (going) wheel so as to stop the rotation of the beam. The lever *j* is connected by a link *k* with another lever *l* fulcrumed at *m* in the frame, and this lever 70 has pivotally connected with it a hook member *n* which projects rearwardly and may be confined to up and down movement on its pivot by a guide *o* on the frame.

p is a rotary element journaled in the 75 frame on a horizontal axis and having an eccentric pin which forms an abutment. The hook member is arranged so that its free or hook end is arranged in the path of and adapted to be engaged and moved by 80 the abutment *q*, such movement when it occurs being to the right and thus adapted to shift the lever *j* clockwise for stopping the rotation of the beam. The element *p* is rotated from the drive shaft *b* by a 85 sprocket and chain connection *r* or in any other way.

It may be stated that so long as all the warp threads remain unbroken and not unduly slack the hook member *n* is elevated 90 on each cycle of the element *p* out of the path of its abutment *q*, so as not to be caught by the latter and stop the rotation of the beam. The means for accomplishing this is as follows: Between the warping machine 95 and a creel *s* of well known type which carries the revoluble spools *t* from which the individual threads of the warp are taken and which has a bar *u* over which and through a reed *v* the warps extends, and which coat with the warping machine to maintain the threads of the warp taut as they are being wound on the beam, is arranged a stand *w* having attached thereto a head *x* formed with a horizontal slot *y* 100 in the end of each of its arms *x'*. In these slots slides a bar *z*, the same being adapted to be reciprocated by the arms of a rock-

ing member 2 fulcrumed in an arm 3 which projects from the stand *w*. A spring 4 connects a third arm of the rocking structure with the stand *w* and acts to shift the 5 rocking structure and hence the bar *z* to the right in Fig. 1. Each movement in the direction indicated is made possible by moving the bar between these movements in the opposite direction, and this is accomplished by a flexible connection 6 attached to the bar centrally thereof and extending back over a pulley 7 on frame *a* and attached to the hook member *n*, which it may now be stated is subject to the depressing 10 action of a rotary cam 8 journaled in frame *a* and adapted to be driven from the drive shaft *b* by a sprocket and chain connection 9 in synchrony with the element *p*. So long as the means *z*⁶ is not prevented from performing 15 its movements to the right it elevates the hook member *n* out of the path of the abutment *q* on each cycle of element *p*; but if its movement to the right is prevented the hook member remains depressed so 20 that it will be caught by the abutment and so stop the rotation of the beam. 25

The means for preventing the movements to the right of the means *z*⁶ when a thread breaks or becomes unduly slack will now be explained: Freely movable vertically in individual holes of bars 10 of a superstructure 11 carried by the arms *x*' of the head *x* of the standard is a series of fallers or detectors 12, each having an eye 12' penetrated by a 30 thread of warp *A*. The warp normally holds all the detectors in the position shown in Fig. 2, so that their lower ends are above the plane of movement of the bar *z*, the normal plane of all the threads being indicated by the line 35 shown solid in Fig. 1. But if a thread breaks or becomes unduly slack the corresponding detector will fall into the path of the bar *z*, thus to stop its movement to the right. There may be an abutment bar 40 45 13 to the right of the lower ends of the detectors to stay them.

It will be understood that the means for effecting the movements of the hook-member *n* out of the path of the abutment *q*, together with the detectors, may be placed elsewhere than as shown so long as the detectors are engaged with the threads between the means for maintaining the warp taut. As herein illustrated this part of the mechanism takes 50 55 the place and makes unnecessary the use of the usual cross-reed by being constructed as follows: The detectors have lateral lugs 12'' and they are arranged so that the lugs of the alternate detectors project oppositely to those of the remainder. In the superstructure is fulcrumed a pair of rockers 14 each having slots 14' to receive a horizontal rod 15 which slides in slots 16 on the superstructure, one such rod being under each 60 65 set of lugs 12''. By manipulating a rocker

to elevate its rod the corresponding detectors can be raised, thus displacing their warp threads out of the plane *A* so that a shed or "cross" is formed by the latter and the remaining (or depressed) threads. 70

Having thus fully described my invention, what I claim as new and desire to secure by Letters Patent is:—

1. The combination, with a rotating beam on which to wind the warp and means co-active with the beam to normally maintain the threads of the warp taut, of a rotary element having an eccentric abutment, means movable to stop the rotation of the beam and arranged in the path of and to be then engaged and moved by said abutment, means, movable in a given direction on each cycle of said element, to move the first means out of said path, detectors each normally urged into position to oppose movement of the second means in said direction but having its movement into such position opposed by a thread of the warp, and means to rotate said element and also move the second means in said direction on each cycle of said element. 75 80 85 90

2. The combination, with a rotating beam on which to wind the warp and means co-active with the beam to normally maintain the threads of the warp taut, of a rotary element having an eccentric abutment, means movable to stop the rotation of the beam and arranged in the path of and to be then engaged and moved by said abutment, an actuating member movable in a given direction on each cycle of said element to pull said means out of said path, a flexible connection connecting said member and the second means, a spring normally urging said member in said direction, a rotary cam to return said second means into said path, detectors each normally urged into position to oppose movement of said member in said direction but having its movement into such position opposed by a thread, and means to rotate said element and cam in synchrony. 95 100 105 110

3. The combination, with a rotating beam on which to wind the warp and means co-active with the beam to normally maintain the threads of the warp taut, of a row of warp displacing devices engaged respectively by threads of the warp at intervals therein and having lateral projections and movable up and down, and up-and-down movable means adapted on movement in one direction to engage the several projections and thereby shift the corresponding devices and thus the threads engaged thereby out of their normal positions. 115 120 125

4. The combination, with a rotating beam on which to wind the warp and means co-active with the beam to normally maintain the threads of the warp taut, of a row of up-and-down movable detectors engaged by the respective threads of the warp and certain 130

of which at intervals in the row have lateral projections, said detectors being normally urged to move in one direction but being held against said movement by the taut warp threads, mechanism, cooperative with each detector upon movement thereof, for causing stopping of the rotation of said beam, and

up-and-down movable means adapted on movement in one direction to engage the several projections and thereby shift the corresponding detectors and thus the threads engaged thereby out of their normal positions.

In testimony whereof I affix my signature.

GEORGE A. CLUFF.
